E. SANDSTROM.

REFUSE CAN.

APPLICATION FILED JAN. 28, 1907, RENEWED APR. 19, 1909.

925,232.

Patented June 15, 1909.

UNITED STATES PATENT OFFICE.

EDWARD SANDSTROM, OF PHILADELPHIA, PENNSYLVANIA.

REFUSE-CAN.

No. 925,232.

Specification of Letters Patent.

Patented June 15, 1909.

Application filed January 28, 1907, Serial No. 354,541. Renewed April 19, 1909. Serial No. 490,963.

To all whom it may concern:

Be it known that I, EDWARD SANDSTROM, residing at Philadelphia, in the county of Philadelphia and State of Pennsylvania, have invented certain new and useful Improvements in Refuse-Cans, of which the following is a specification.

My invention relates to certain new and useful improvements in refuse cans, and it more particularly has for its object to provide a can of this character of a very simple and effective construction, which can be easily and cheaply manufactured at a minimum cost and which can be readily attached 15 to the ordinary fence.

Generically, the invention comprises a hinged gate in the fence to which a can is secured, the can having a hinged top through which the refuse is dumped into the can.

20 In its more subordinate nature the invention comprises certain novel construction, combination and arrangement of parts, all of which will be first described in detail, and then be specifically pointed out in the appended claim, reference being had to the accompanying drawings, in which:—

Figure 1, is a perspective view of the invention. Fig. 2, is a rear elevation thereof. Fig. 3, is a central, vertical section on the 30 line 3—3 of Fig. 2, showing the can in its normal position. Fig. 4, is a similar view showing the can being dumped.

Referring now to the accompanying drawings, in which like letters and numerals of reference, indicate like parts in all of the figures, 1 designates the fence which includes the parallel boards 1^a from which a section is sawed out to form the door or trap 2, the boards 2^a of which are braced by strips 3 which are nailed, screwed or otherwise fastened to the boards as at 3^a to hold them together. The fence boards 1^a are likewise braced where cut, by strips 4 secured at 4^a to the boards.

40 45 The can 5 comprises the bottom 5^a, sides 5^b and back and front portions 5^c and 5^d respectively, the back 5^c being larger than the front 5^d to leave an opening or beveled mouth over which the lid 6 is hinged as at 6^a

to the front 5^d of the can and has a handle 50 6^b by means of which it can be swung over.

The can is screwed to the door 2 by screw bolts or otherwise as at 7 and the door 2 is hinged at 2^x to the fence to swing on a horizontal axis.

55

A handle 8 is provided on the door 2 by means of which it may be manipulated.

The lower portion of the can abuts the fence boards and hence serves as a stop to limit the movement of the door 2 to its 60 normal position.

In the practical application of my invention, the garbage or other refuse is placed in the can through the mouth thereof, and when it is desired to dump the same, the 65 operator grasps the handle 8 and swings the door and can in the direction of the arrow in Fig. 2, to bring it to the position shown in Fig. 3, when the contents thereof will be ejected. By reason of the manner of mounting the can door it will open by gravity as the can is emptied and close again as the can is returned to its normal position.

70 75 From the foregoing description taken in connection with the accompanying drawings it is thought the complete construction, operation and numerous advantages of my invention will be readily understood by those skilled in the art to which the invention appertains.

80 85 What I claims is:—

A can comprising in combination with a fence or support consisting of a plurality of boards, said boards having a can aperture therein, braces on one side of said boards 85 for holding said boards together at such aperture, a door for said aperture formed of a series of boards and braces on one side thereof for holding the door boards together, the braced sides of the door boards and fence 90 boards lying in the same plane, hinges connecting said door with said fence at the bottom thereof, a refuse can secured to the braced side of the door to swing therewith, said can projecting below the pivot ends of 95 the door to lie in contact with the fence boards and form a stop for holding the door in the same plane as the fence when the door

is shut, said can comprising a body of rectangular cross section and having a beveled mouth, a lid hingedly secured to the front top edge of the can to close over the beveled mouth, a handle secured to the lid, a handle secured to the door at the opposite side of the can, said lid being arranged to open by gravity, as the door is swung out to dump

the can, the back surface of the can lying wholly in a single plane, substantially as shown and described.

EDWARD SANDSTROM.
